(57) **CLAIM**

I claim the ornamental design for the optics adapter, as shown and described.

DESCRIPTION

FIG. 1 is a front view of the optics adapter, the rear being a mirror image;

FIG. 2 is a front-elevation view of FIG. 1, the rear side being a mirror image;

FIG. 3 is a side view of FIG. 1, the right side being a mirror image; and

FIG. 4 is a top view of FIG. 1;

FIG. 5 is a bottom view of FIG. 1;

FIG. 6 is an installed front-elevation view of FIG. 1, the right side being a mirror image;

FIG. 7 is an installed front view of FIG. 1, the rear side being a mirror image; and,

FIG. 8 is an installed side view of FIG. 1, the right side being a mirror image.

The broken lines are shown to illustrate unclaimed portions of the invention and form no part of the claimed design. This embodiment is an optics adapter used on the riser for a firearm.
